UNITED STATES PATENT OFFICE

HERMAN J. HAMMERLY, OF WALLINGFORD, CONNECTICUT, ASSIGNOR TO THE TRUMBULL ELECTRIC MANUFACTURING COMPANY, OF PLAINVILLE, CONNECTICUT, A CORPORATION OF CONNECTICUT

ELECTRIC SWITCH

Application filed January 29, 1929. Serial No. 335,891.

My invention relates particularly to quick-make and -break switches. The main object is to provide a simple but reliable and durable shock absorbing and connector means which is particularly applicable to switches of the slate base type. Such mechanisms are subjected to severe shock in the closing movement and the parts consequently frequently work loose or become broken. One of my objects accordingly is to so construct and arrange the parts as to cushion the impact and thus minimize the danger of fracture or loosening of the parts. Another object is to provide a construction of a character which will prevent or minimize arcing between the movable blade and the stationary jaw post in the opening movement of the switch.

In the accompanying drawings I have illustrated a desirable form of mechanism involving my invention. The preferred form of quick-make and -break mechanism is more fully shown, described and claimed in my application No. 280,088 filed May 23, 1928. The switch base will usually be formed of slate and may, as illustrated, be mounted in any suitable form of box. The contacts, terminals, and circuit protecting fuses may be of any suitable character. The switch proper may include any number of movable blade units as for instance 2, as shown herein. Each unit is mounted on the insulating base and has a blade hinged in the usual manner and adapted to engage a suitable jaw or contact member. An operating crank and a quick-break mechanism are mounted in a suitable enclosing box and provided with an external operating handle.

The connection between the crank and each switch blade is effected by an insulating bar or plate, preferably of fibre or the like, having a slotted connection with the crank and being riveted to the blade. This plate extends beyond the blade and serves as a shock absorbing abutment to the blade at the end of the circuit closing movement and also as a stop for limiting the throw of the blade. This plate is so located as to pass close to the contact jaw in the circuit opening move-

ment and thus interrupt or diminish any arc which tends to form.

Fig. 1 is a perspective view of an enclosed switch involving my invention, the cover being shown open and partly broken away and the switch being in a closed circuit position.

Figs. 2, 3 and 3^a are perspective views of switch blades and their attached insulating connectors, which serve as shock absorbers and arc interrupters showing three modifications.

Fig. 4 is a vertical section and side elevation of one of the switch units in a closed circuit position.

Fig. 5 is a similar view in a circuit opening position.

Fig. 6 is an edge view of one of the switch units in a circuit opening position showing a modified form of connector.

Fig. 7 is a similar view of another modified form of connector.

The box 10 in the form shown has a hinged cover 11. These may be of any suitable form and provided with catches, etc. as is common in the art.

The switch base 12 is usually of slate or other suitable insulating material and suitably connected to the bottom of the box.

Each switch unit has circuit terminals 13 and 14 and clips 15 and 16 for the fuse 17. The stationary contacts of the switch unit are in the form of a post 18 and the spring jaws 19. In the particular form shown the movable switch member 20 has an end hinged to the post 18 and the other end adapted to engage the jaws 19. Each movable switch member or blade 20 is provided with a connector plate 21 preferably formed of fibre riveted at 22 to the blade.

Any number of these switch blade units may be employed and may be arranged so as to be operated by a crank 23, which is pivotally supported in opposite sides of the box. Each of the plates 21 has an open notch 23' to receive the crank so that the various switch blades are independently connected to the crank 23.

In the co-pending application above referred to I have shown the details of the quick-make and quick-break mechanism in

the preferred method of supporting the movable parts. It is sufficient to note that for the purpose of this application I prefer to utilize a bushing 24 which is rotatably mounted on one wall of the box and serves as a bearing for one end of the crank 23. The throwing disc 25 is rotatably mounted on this bushing and is suitably connected to the throwing spring 26 which has a stationary abutment 27. The handle 28 is mounted on the outer end of the bushing 24 and has a suitable lost-motion connection through the wall of the box with the disc 25, which in turn has a lost-motion connection with the crank 23. The quick-break mechanism, as its name implies, opens the switch with a snap action and closes the switch with a snap action. The shock of the opening movement is taken up by the stationary bracket 29 secured to the inside of the box. The shock of the closing movement is taken up by the impact of the lower ends 30 of the various connectors above described. These connectors being of more or less yielding or resilient material, serve as non-metallic shock absorbers which distribute the impact or stress without tending to crack or chip the base. When the circuit is opened the corner of the insulating plate snaps past the edge 30 of contact jaw 19 and thus tends to cut off or obstruct any arc which may tend to form. It will thus be seen that the insulating plate 21 serves the quadruple purpose of a convenient connector between the crank 23 and the switch blade 20, an arc interrupter, and as a stop for blades in the closing movement and as a shock absorber.

In the form shown in Fig. 6 the lower end of the connector 21 is broadened out at 31 beneath the blade so as to provide a wider foot for distributing the shock of the circuit closing movement and for interrupting any arc which tends to form.

In the form shown in Figs. 3 and 7 there are two plates 21 and 21' on opposite sides of the blade 20 with an intervening insulating layer 32 between their lower ends beneath the blade. This gives additional reinforcement to the shock absorbing feature and also provides additional arc interrupting material at the most effective position.

In the form shown in Fig. 3^a two insulating plates are slotted or recessed to receive the blade between them and are riveted to the blade as in the other forms. Obviously this arrangement provides a method for making the connectors of as great a thickness of material as may be desired and also for closing the space between the two parts of the connector.

While I have described my shock-absorbing connector means as particularly well adapted for use in quick-make switch constructions, it will be readily understood that it may be very useful in other forms of switch construc-

tions, for instance, in ordinary hand operated knife switches.

It should be understood that other changes in construction and arrangement may be made without departing from the spirit or scope of my invention.

I claim:

1. In an electric switch, an insulating base a switch unit carried thereby, said unit including a movable blade and a stationary jaw to receive a movable end of the blade, an operating crank for said blade, and a non-metallic plate riveted to said switch blade and having a loose connection with said crank and having a foot for striking against the base in the circuit closing movement of the switch and serving as an arc interrupter in the circuit opening movement.

2. In an electric switch, a base, a plurality of switch units carried thereby, each unit including a hinged blade and a stationary jaw to receive the movable end of the blade, an operating crank for said blade and a fibre plate secured to each switch blade and connectible to said crank independently of the other blades, each plate having an extension for abutting against the base in the circuit closing movement and serving as an arc interrupter in the circuit opening movement of the switch.

3. In an electric switch, an insulating base, a switch unit carried thereby, consisting of a supporting post, a blade hinged to said post and a stationary jaw to receive the movable end of the blade, an operating crank for said blade and a resilient plate secured to said switch blade said plate having a slotted connection with said crank and having a foot for abutting against the base in the circuit closing movement and said foot serving as an arc interrupter in the circuit opening movement of the switch.

4. In an electric switch, a base, a plurality of switch units carried thereby, each unit consisting of a supporting post, a blade hinged to said post and a stationary jaw to receive the movable end of the blade, an operating crank for said blade and an insulating plate secured to each blade and connectible to said crank independently of the other blades, each plate having a foot for abutting against the base in the circuit closing movement and said foot serving as an arc interrupter in the circuit opening movement of the switch.

HERMAN J. HAMMERLY.
